(57) **CLAIM**

The ornamental design for an animal feeder including a backboard and a vertically adjustable feeder dish support, as shown and described.

DESCRIPTION

FIG. 1 is a front elevational view of an animal feeder including a backboard and a vertically adjustable feeder dish support showing our new design;

FIG. 2 is a rear elevational view thereof;

FIG. 3 is a bottom plan view thereof;

FIG. 4 is a top plan view thereof;

FIG. 5 is a right side elevational view thereof, the left side elevational view being a mirror image thereof;

FIG. 6 is an upper right side perspective view thereof; and,

FIG. 7 is an exploded upper right side perspective view thereof, similar to FIG. 6 and showing the feeder dish support separated from the backboard, and indicating the several positions at which the feeder dish support may be located on the backboard.
